Attorney

UNITED STATES PATENT OFFICE.

THOMAS W. ROACH, OF SEATTLE, WASHINGTON.

OIL BURNER.

Application filed August 27, 1926. Serial No. 131,963.

My invention relates to oil burners of a type designed for using heavy fuel oil and in which a rotating distributor is used which, in conjunction with the air blast, results in sufficient atomization of the oil to insure its combustion.

The object of my invention is to produce a burner capable of handling the heavy oils and in a size which is adapted for use in furnaces such as are used for heating buildings. My invention consists of certain constructions and combinations of parts which will be hereinafter described and then particularly defined by the claims.

15 The accompanying drawings illustrate a construction in which my invention has been embodied, the specific construction illustrated being one which is now preferred by me.

20 Figure 1 of the drawings is a vertical cross section through the grate and the oil and air supplying and distributing mechanisms, the plane of section being illustrated by the broken line 1-1 of Figure 2.

25 Figure 2 is a top-plan view of the mechanism shown in Figure 1, the upper plates of the distributor being broken away at one side to better show its internal construction.

The device illustrated is of a type of construction adapted for use in an ordinary house-heating furnace or other furnace. This furnace may be a hot-air furnace, a hot-water furnace, or a steam furnace. The walls 15, shown in Figure 1, represent the 30 lower portion of the fire pot or furnace chamber proper. These would preferably be of some refractory material such as fire clay or bricks. The fire grate employed is also preferably of the same type of material.

35 This fire grate 1 is composed of a series of bricks of segmental shape, which, when assembled, make a circular grate. These segmental sections are cut off at their inner ends sufficiently to furnish an opening for the reception of component parts of the burner.

40 Concentrically of the grate at its center is the oil distributor, which as a whole is indicated by the character 2. This oil distributor has a top plate or plates 20 and a bottom plate 21, these being spaced apart so as to form a disc-like structure, tapering towards 45 its outer edge. As illustrated, the upper disc 20 is in reality composed of two plates separated slightly. These are secured together so as to be mechanically considered the equivalent of one plate. The object in

using two spaced plates for the top member is merely to give heat protection to the parts beneath it.

The upper and lower plates of the oil distributor are connected and spaced apart by radiating webs 3, making it in effect a fan wheel. These webs extend from the outer edge or periphery of the discs only part way to the center, stopping sufficiently short of the center to accommodate the other parts of the burner which are located on the central axis. The lower plate 21 is provided with a central opening 22 of sufficient size to accommodate the disc-supporting and oil supplying members and also to provide ample inlet for the air used in combustion.

45 Centrally positioned in and secured to the distributor discs is a distributor head 4. This is hollow and has oil distributing pipes 41 radiating therefrom and extending outwardly approximately to the periphery of the distributor. The exact length of these pipes is, however, not a material matter. These are so placed that oil supplied from 50 the chamber in the head 4 will be discharged through the pipes 41 when said head and distributor as a whole is revolved.

55 The oil distributor as a whole is mounted so as to rotate about a vertical axis. The head 4 is carried upon the upper end of a tubular shaft 50, which shaft at its upper end communicates with the chamber in the head 4 and at its lower end with a source of supply of oil. This shaft is journaled in a 60 casing member which is in the form of a tube 5. To insure a non-leaking joint at the upper ends of the tubular casing member 5, I have shown the head 4 as being provided with a shell-like apron 40 which fits closely 65 over the upper end of the tubular casing 5.

70 The lower end of the tubular casing 5 is supported from a horizontal casing member 6 to which oil is supplied in any suitable and convenient manner. The method illustrated for doing this is to secure the lower end of the casing member 5 into a nut 51, which screws into the casing 6. Casing 6 is also shown as having a horizontal tube or pipe 60 screwing thereinto and forming the fuel supply conduit. The tubular pipe 50 opens 75 at its lower end into the chamber in the casing member 6.

75 To the lower end of the tubular shaft 50, which extends into the chamber in the casing 6, is secured a beveled gear 61, with which meshes another gear 62, carried by a hori-

2
zontally extending shaft 63, which shaft is journaled in or supported from the casing 6 and 60. These gears are thus immersed in the fuel oil supply and are lubricated 5 thereby.

The fire grate 1 has an upper surface of peculiar shape. Just without the periphery of the distributor 2 it has a drip groove or channel 10. This is of such shape that 10 any oil discharged upon the grate and unburned and which flows in that direction will be caught and held until it has been consumed. Outwardly from the drip channel 10 is an upstanding flange 11, which flange is 15 so positioned that it will receive thereon the oil discharged from the revolving distributor pipes 41. Just outwardly of this flange is a combustion channel 12, which preferably has its outer wall 13 undercut, as is shown 20 in Figure 1. Outwardly of this channel the grate has an outward and upwardly curving surface 14, against which the flames will impinge and be deflected upwardly.

To prevent the possibility of carbon collecting upon the surface 11, I have provided 25 the rotating distributor with two scraper fingers 7. These project beyond the periphery of the distributor discs and have their outer end and one side face positioned 30 to swing over and fairly close to the surface of the fire grate which includes the inner face of the flange 11 and the flat ledge inwardly therefrom. Should carbon collect upon these surfaces in any material amount, 35 it is liable to interfere with the proper combustion of the oil. These scraping fingers will remove any carbon forming upon these surfaces by the time it has reached any material thickness.

40 The oil supply casing 6 and the parts carried thereby are in turn enclosed within an outer casing 8, which is used as an air supply conduit and as well as a support for the burner and its operating parts. 45 This conduit has an upper extension 80 which at its upper end is engaged by the inner ends of the segments which form the fire grate 1. This forms an annular channel surrounding the tubular casing 5, through 50 which air is supplied to the interior of the rotating distributor.

The shaft 63 is rotated by any suitable means. This results in rotating the tubular shaft 50 and the distributor 2. The rotation 55 of the distributor causes the oil distributing arms 41 to function as a centrifugal suction pump to draw up the oil and to discharge it upon the fire grate. It is contemplated that the oil be provided for the burner and maintained at a level either slightly below the discharging point at the distributor, or, be furnished thereto under a sufficient pressure to insure a positive flow of the oil. Either 60 method may be employed with this burner.

65 As the oil is discharged from the radiating

pipes 41 air is also discharged, due to the fact that the vanes 3 which connect the upper and lower disc members serve as fan blades or impellers, to thereby discharge the air with considerable force. This discharged air 70 acts in a measure to atomize the oil.

In starting a burner of this sort, when fuel oil is used, it will be necessary to provide a priming heat. This I contemplate doing by the use of a small auxiliary burner, 75 which burner is contained within a casing represented in Figure 2 at 9. This may be any type of burner employing an oil sufficiently volatile that it may be ignited by ordinary means, such, for instance, as by 80 the use of an electric spark. This burner discharges its flame through a tube 90, which is so directed as to discharge upon the grate just without the distributor.

I have found, by experience, that the use 85 of a channel 12, which I have termed a combustion channel, at the point bearing the relation to the other parts as indicated in Figure 1, is a matter of some importance. A greater part of the discharged oil will flow 90 over the upper edge of the flange 11 and is also carried by its velocity across the channel 12, and flows up the inclined surface 14. When the burner is in action, a ring 95 of flame follows around in the channel 12, through which flame the oil passes. In doing this it is so heated as to be ignited and complete combustion is secured. The undercutting of the outer side wall 13 causes a rotating effect to be produced in the channel 12, keeping this channel filled with flame 100 which heats the discharged oil.

In starting my burner the auxiliary burner is employed for a short time, the fuel oil not being turned on until somewhat later. 105 After the pilot or priming burner has somewhat heated the grate, the fuel oil is supplied and after this is burning well and the grate is well heated the auxiliary burner is turned off.

The oil distributing pipes 41 are preferably placed just in advance of the air impellers or vanes 3, from which it results that the strongest rush of air outwardly flows against and along said pipes, thereby very materially cooling them and preventing carbonization of the oil flowing therethrough.

What I claim my invention is:

1. An oil burner comprising a rotative distributor, a fire grate surrounding said distributor and having an upstanding circular flange positioned to receive the discharge from said distributor against its inner face, a depressed channel just without said flange and a wall just outside of said channel and extending upwardly therefrom.

2. An oil burner comprising a rotative distributor, a fire grate surrounding said distributor and having an upstanding circular

flange positioned to receive the discharge from said distributor against its inner face, a depressed channel just without said flange and a wall just outside of said channel and extending upwardly therefrom, and a drip channel located inwardly of said upstanding flange.

3. An oil burner comprising a rotative oil distributor and air blower, a hollow supporting shaft through which oil is supplied to the distributor, a horizontal drive shaft and gears connecting said shafts, a casing in which both shafts are journaled and through which oil is supplied, and an outer casing surrounding said first casing and forming the air supply conduit for the distributor.

4. An oil burner comprising a rotative distributor for both air and oil, a fire grate surrounding the distributor and having an upstanding flange positioned to receive the impact of air and oil as discharged from the distributor, and a channel in the fire grate just outside of said flange, the outer wall of said channel being undercut.

25 5. An oil burner comprising a combined air fan and oil distributor rotative about a vertical axis, and a fire grate surrounding said distributor and having a drip groove in its upper surface just without the periphery 30 of the distributor, an upstanding flange outside of said drip groove positioned to receive the discharge from the distributor, and a depressed channel just outside of said

flange, the outer side wall of said channel being undercut, and an upwardly curving surface outside of said channel.

6. In an oil burner, an oil and air distributor, a tubular vertical shaft carrying the distributor upon its upper end and also functioning as the oil supply conductor, a 40 tubular vertical casing surrounding said shaft and providing a bearing therefor, a horizontal casing supporting said vertical casing and also functioning as an oil supply conduit, a drive shaft journaled in said horizontal casing, gears connecting said shafts and immersed in the oil supply, and an air supply casing surrounding said oil supply conduit and having an upward extension 45 surrounding the vertical casing which surrounds the tubular shaft and opening to the distributor.

7. A fire grate for use with oil burners employing a rotary distributor having an annular shape and provided with an oil drip groove towards its inner edge, an upstanding circular flange positioned outside of said drip groove and to receive the oil discharge, an ignition channel surrounding said flange and having an undercut outer wall, and an upwardly and outwardly extending combustion surface without said ignition channel.

Signed at Seattle, Washington, this 20th day of August, 1926.

THOMAS W. ROACH.
